United States Patent Office

Des. 180,720
Patented July 30, 1957

180,720

BED TABLE OR SIMILAR ARTICLE

Roy E. Orvedahl, Minneapolis, Minn., assignor to Vulco Craft, Inc., Minneapolis, Minn., a corporation of Minnesota

Application September 7, 1956, Serial No. 42,865

Term of patent 3½ years

(Cl. D33—14)

FIG. 1

FIG. 5

FIG. 2

FIG. 3

FIG. 4

Fig. 1 is a perspective view of a bed table or similar article embodying my design;

Fig. 2 is a top plan view thereof;

Fig. 3 is a right side elevation view;

Fig. 4 is a front elevation view; and

Fig. 5 is a bottom plan view thereof.

I claim:

The ornamental design for a bed table or similar article, as shown.
